SPOON OR SIMILAR ARTICLE

Henri Asa Horton, Vernon, N.Y., assignor to Oneida Ltd.,
Oneida, N.Y., a corporation of New York

Filed June 3, 1960, Ser. No. 60,841

Term of patent 14 years

(Cl. D54—12)

FIG. 3.

FIG. 2.

FIG. 1.

FIG. 4.

FIG. 5.

Fig. 1 is a front elevational view of a spoon showing my new design;

Fig. 2 is a side elevational view;

Fig. 3 is a rear elevational view; and

Figs. 4 and 5 are sections on the respective lines 4—4 and 5—5 of Fig. 1.

The essential features of my design for a spoon or similar article reside in the configuration of the handle in combination with the particular type of ornamentation as applied thereto.

I claim:

The ornamental design for a spoon or similar article, substantially as shown and described.
